UNITED STATES PATENT OFFICE.

GEORGE E. SAVAGE, OF MERIDEN, CONNECTICUT, ASSIGNOR TO THE
MANNING BOWMAN & COMPANY, OF SAME PLACE.

LEMON-SQUEEZER.

SPECIFICATION forming part of Letters Patent No. 628,254, dated July 4, 1899.

Application filed March 17, 1899. Serial No. 709,507. (No model.)

To all whom it may concern:

Be it known that I, GEORGE E. SAVAGE, of Meriden, in the county of New Haven and State of Connecticut, have invented a new 5 Improvement in Lemon-Squeezers; and I do hereby declare the following, when taken in connection with the accompanying drawings and the letters of reference marked thereon, to be a full, clear, and exact description of the 10 same, and which said drawings constitute part of this specification, and represent, in—

Figure 1, a view, partly in side elevation and partly in section, of a lemon-squeezer constructed in accordance with my invention; 15 Fig. 2, a detached plan view of the supporting-ring; Fig. 3, a detached reverse plan view of the juice-cup; Fig. 4, a detached plan view of the compression-cone and juice-cup; Fig. 5, a sectional view showing the mode of swiveling the compression-cup upon the lower end 20 of the plunger; Fig. 6, a view in transverse section on the line *a b* of Fig. 5.

My invention relates to an improvement in lemon-squeezers of the type which are adapted to be clamped upon a shelf or table and to 25 be operated by the manipulation of a lever, the object being to produce a simple and effective device composed of few parts and adapted to be readily cleaned.

With these ends in view my invention consists of a lemon-squeezer having certain details of construction and combinations of parts, as will be hereinafter described, and pointed out in the claims.

In carrying out my invention as herein shown I employ a suitable cast-metal frame A, provided with a supporting-arm B and a clamping-arm C, both extending inward in the same direction, located one above the 40 other, and sufficiently separated from each other to receive the edge of a table or shelf between them. A clamping-screw D, mounted in the lower arm, provides for clamping the device upon the shelf or table. The said

frame is formed with a vertically-arranged tubular bearing E for a plunger F, having its upper end slotted for the reception of the inner end of an operating-lever G, which is pivotally connected with the plunger by means 45 of a pivot H, the said lever having its inner

end bowed inwardly and formed with a slot I, receiving a pin J, mounted in the frame, with which the lever is thus connected. The lower end of the plunger is furnished with an inverted compression-cup K, having its interior surface furnished with ribs and provided with a handle L, the said compression-cup being swiveled upon the lower end of the plunger, to which it is so connected by means of a pin M. The handle L of the compression-cup provides for turning it after it has been crowded down upon the lemon, whereby the action of the device is made more perfect. This cup coacts with an externally-ribbed cone N, the external diameter of which corresponds in a general way to the internal diameter of the compression-cup. The lower ends of the ribs of this cone extend outward to form radial fingers O, the spaces between which receive lugs or projections P, formed within the removable juice-cup Q, whereby the cone is held against rotation. The juice-cup Q is set down within a supporting-ring R, made integral with a vertically-arranged bearing S, by means of which the ring is secured to 75 the lower portion of the frame by means of a screw T or equivalent instrumentality. The supporting-ring R is formed with an internal flange U, provided with three lugs V, entering into recesses W formed in the bottom of 80 the juice-cup Q in the production of the upwardly-extending projections P before mentioned. By means of this construction the cone N is held against rotation within the juice-cup Q and the juice-cup Q is held 85 against rotation within the supporting-ring R, the cone being locked against rotation in any position in which it may be entered into the juice-cup, for the reason that it is provided with a complete series of locking-spaces 90 formed between its radial fingers O.

A rod secured to the extreme lower end of the frame in a vertical position supports a shelf or frame Y, upon which a tumbler or other vessel Z is placed for catching the juice 95 flowing downward through the juice-cup Q and supporting-ring R.

It is apparent that in carrying out my invention some changes from the construction shown and described may be made, and I 100

would have it understood that I do not limit myself strictly thereto, but hold myself at liberty to make such variations as fairly fall within the spirit and scope of my invention.

5 Having fully described my invention, what I claim as new, and desire to secure by Letters Patent, is—

1. In a lemon-squeezer, the combination with a frame adapted to be secured to a table or shelf, of a vertically-movable plunger mounted in the said frame, an operating-lever connected with the upper end of the plunger, an inverted compression-cup applied to the lower end of the plunger, a supporting-ring formed independently of the frame and secured to the lower end thereof, a removable juice-cup located in the said ring in which it is held against rotation, and a non-rotatable, removable cone formed independently of and adapted to be located within the juice-cup and provided with external ribs terminating at their lower ends in radial fingers which are employed for preventing the cone from rotation within the juice-cup which is provided with projections adapted to extend between the said radial fingers of the cone which is thus held against rotation within the cup.

2. In a lemon-squeezer, the combination with a frame adapted to be clamped upon a shelf or table, of a vertically-arranged plunger mounted in the said frame, an operating-lever connected with the upper end of the plunger, an inverted compression-cup swiveled upon the lower end of the plunger and provided upon its edge with a handle by means of which it is turned, a supporting-ring made independently of and secured to the lower end of the frame, a removable juice-cup adapted to be set within the said ring in which it is held against rotation, and a removable cone formed independently of and adapted to be set within the said juice-cup and provided with external ribs, the lower ends of which terminate in radial fingers, the spaces between which receive projections formed within the bottom of the juice-cup, in which the cone is thus held against rotation.

In testimony whereof I have signed this specification in the presence of two subscribing witnesses.

GEO. E. SAVAGE.
